UNITED STATES PATENT OFFICE.

ALBERT L. LANGFORD, OF VANCOUVER, BRITISH COLUMBIA, CANADA.

LOOSE-LEAF BINDER.

1,092,060.

Specification of Letters Patent. Patented Mar. 31, 1914.

Application filed April 8, 1913. Serial No. 759,710.

To all whom it may concern:

Be it known that I, ALBERT L. LANGFORD, a citizen of Canada, residing at Vancouver, in the Province of British Columbia and in the Dominion of Canada, have invented new and useful Improvements in Loose-Leaf Binders, of which the following is a specification.

The invention relates to binders of the loose leaf type and has for an object to provide a device for carrying file wrappers.

The invention embodies, more particularly, a binder adapted for binding together a number of sheets of paper and whereby a sheet of paper or plurality of sheets of paper can be added to or removed from a file at any time or from any part of the file.

The invention further embodies a binder which is preferably used in connection with a folder and adapted particularly for use in vertical filing systems whereby papers securely fastened within the folder are identified upon a tab or other projecting member constituting a part of the folder and designating the contents thereof.

In the further disclosure of the invention reference is to be had to the accompanying drawings, constituting a part of this specification, in which similar characters of reference denote corresponding parts in all the views, and in which:

Figure 1 is a fragmentary perspective view of the folder, showing my binder attached thereto; Fig. 2 is a fragmentary rear elevation of the folder, showing the rear part of the binder; Fig. 3 is a vertical longitudinal sectional view taken through the folder and binder; Fig. 4 is a vertical transverse sectional view taken through the folder and binder; Fig. 5 is a perspective view of the securing plate forming a part of the binder; and Fig. 6 is a perspective view of the tape-carrying member showing the tape thereon.

Referring more particularly to the views, I provide a folder 10 preferably including an offset tab 11 on which is adapted to be printed or written matter which will identify the contents of the folder 10 and which is provided to receive letters or other file wrappers 12.

A tape-carrying member 13 preferably formed of cloth gummed on the inner face is provided with pairs of parallel slots 14 through which a tape 15 is passed, with the portions of the tape between the pairs of slots glued or otherwise secured to the inner face of the tape-carrying member 13, the

said inner face of the tape-carrying member being preferably provided with gum so that the tape-carrying member can be secured on the rear outer face of the folder 10, with the said rear face of the folder having a plurality of apertures 16 adjacent which the pairs of slots 14 lie so that the free ends of the tape 15 can be passed through the apertures 16, as will be apparent by referring to the views.

The letters 12 are provided with perforations 17 and after the letters have been placed in the folder 10 the free ends of the tape 15 are passed through the perforations 17.

A securing plate 18 is provided and is preferably made of a single piece of cardboard, leather or other suitable material, the said securing plate having centrally arranged slots 19 formed in the ends thereof, buttons 20 being carried on the upper face of the securing plate 18 by means of pins 21 passing through the buttons and the securing plate so that the buttons will be rigidly carried on the upper face of the securing plate adjacent the inner ends of the slots 19. Now when the letters 12 have been arranged in the folder in the manner mentioned, the securing plate 18 is placed on the uppermost letter or sheet and it will be seen that the slots 19 will register with the perforations 17 in the letters so that the free ends of the tape 15 will pass through the slots 19, after which a pull is exerted on each free end of the tape and the same is then wound around each of the buttons 20 carried on the securing plate 18, thus not only securing the letters 12 to the folder 10 and within the same, but frictionally binding the letters together so as to prevent the same from accidentally tearing or being ripped out of the folder 10.

It will be apparent that the binder described can be cheaply constructed, the tape-carrying member 13 being preferably formed of a stout cloth and the tape 15 being also preferably formed of cloth, while the securing plate 18 and buttons 20 are preferably formed of cardboard, thus providing a simple and efficient article which can be either manufactured with the folder or independently thereof and readily attached to the folder to accomplish the desired result.

Having thus described my invention, I claim:

1. In a loose leaf binder, the combination with a folder adapted to contain letters having perforations therein, of a tape-carrying

member secured to the back of the folder and provided with pairs of slots registering with apertures in the back of the folder, a tape passing through the pairs of slots and adapted to pass through the apertures in the back of the folder, with the portion of the tape between the slots of the tape-carrying member secured to the tape-carrying member, the free ends of the tape being adapted to pass through the perforations in the said letters, a securing plate having longitudinal slots formed in the ends thereof and adapted to repose on the uppermost letter, with the slots of the plate registering with the perforations in the letters and the said tape passing through the slots, and buttons carried on the upper face of the securing plate, adjacent the inner ends of the slots and adapted to have the free ends of the tape attached thereto to securely bind the letters in the folder.

2. A loose leaf binder for folders adapted to contain letters, consisting of a tape-carrying member glued to the back of the folder, a tape on the member and passing through apertures in the back of the folder and adapted to pass through perforations in the said letters with a portion of the said tape lying between the back of the folder and the tape carrying member and glued thereto, a securing plate provided with slots adapted to register with the perforations in the letters, and buttons on the securing plate and adapted to have the free ends of the tape wound around the same to bind the said letters in the said folder.

In testimony whereof I affix my signature in presence of two witnesses.

ALBERT L. LANGFORD.
